Filed Jan. 9, 1961, Ser. No. 81,612
1 Claim. (Cl. 123—73)

This invention relates to two-stroke engines having a device for automatic gradual timing of the closure of the inlet port, adapted to gradually delay closure as the rate of speed rises. With this device highest efficiency is obtained from the engine at various rates of speed.

The engine will be described with reference to the accompanying drawings which show an embodiment by way of example.

FIGURE 1 is a front view of the engine with the cover plate removed and the shaft sectional along line I—I of FIGURE 3;

FIGURE 2 is a sectional view of the engine on line II—II of FIGURE 1.

FIGURE 3 is a sectional view of the timing device on line III—III of FIGURE 1.

Reference 5 denotes the two-stroke engine cylinder, 6 is the piston thereof, 7 and 8 are the inlet and outlet ports, respectively.

The two-stroke engine is of the conventional crankcase compression type.

The timing device is arranged at one end of the engine crank-shaft 2 and comprises a rotary disc 9 from which a sector is removed over a predetermined angular width confined by the radial edges 10, 11, thereby providing a control port in the disc. The rotary disc times the fuel inlet to the engine through the above control port and suction port 7. As the engine rate of speed varies the angular position of the disc 9 with respect to the shaft 2 is automatically controlled by means of centrifugal weights 14 pivoted at 13 to a plate 12 secured to the

2

end of the shaft 2. The centrifugal weights 14 are formed with toothed sectors 16 constantly meshing with a pinion 17 loosely mounted on the shaft 2 and having keyed thereto the disc 9.

It will be clear that as the rate of speed of the shaft 2 rises, the centrifugal weights 14 expand against the action of springs 15 thereby effecting through their toothed sectors 16 an angular displacement of the pinion 17, hence of the disc 9 to time inlet with respect to the shaft 2. The timing action is therefore gradual as the rate of speed increases.

What I claim is:

A two-stroke engine comprising a crankcase, a crank-shaft rotatable in the crankcase, an inlet port in one of the end walls of the crankcase, and an automatic timing device controlling the said port comprising a support plate fixed to one end section of the crankshaft, a centrifugal weight pivotally supported from the plate including a toothed sector thereon, a pinion concentrical with the said end section of the crankshaft meshing with the said toothed sector in a mutual arrangement whereby centrifugal force acting on the weight on operation of the engine will angularly shift the pinion in a direction opposite to the rotation direction of the shaft, spring means urging the weight towards the shaft, and a disc-shaped shutter member fast with the said pinion controlling the said inlet port.
